UNITED STATES PATENT OFFICE.

WILLIAM KYLLONEN, OF OAKES, NORTH DAKOTA.

WIRE-FENCE TOOL.

1,158,242.

Specification of Letters Patent. Patented Oct. 26, 1915.

Application filed April 24, 1915. Serial No. 23,667.

To all whom it may concern:

Be it known that I, WILLIAM KYLLONEN, a citizen of the United States of America, residing at Oakes, in the county of Dickey 5 and State of North Dakota, have invented certain new and useful Improvements in Wire-Fence Tools, of which the following is a specification.

The present invention relates to improvements in wire-fence tools, designed for use 10 in the erection of wire fences, and similar structures.

The primary object of the invention is the provision of a special tool to be used 15 with a special form of staple and metallic post, in the erection of wire fences, by means of which the horizontal strands or wires of the wire fence are affixed to the uprights or posts of the fence. While I 20 shall hereinafter confine the description of the invention to wire fences and their erection, it will be clearly understood of course that the invention contemplates use of the tool or implement in other connections with 25 other similar structures.

The invention consists in certain novel features and combinations and arrangements of parts as will be hereinafter fully described and claimed.

30 In the accompanying drawings I have illustrated one complete example of the physical embodiment of my invention constructed according to the best mode I have so far devised for the practical application 35 of the principles of my invention, and I have illustrated one manner of using the tool.

Figure 1 is a plan view of a tool embodying my invention. Fig. 2 is a side elevation 40 of a portion of the tool of Fig. 1. Fig. 3 is a perspective view of the anvil of the tool. Fig. 4 illustrates a portion of the tool, in position after it has been manipulated to fix a staple to a post and attach the wire. 45 Fig. 5 is a view illustrating in perspective, a staple and fence wire applied to a post by my device. Fig. 6 illustrates the special staple before it is applied to the post.

In the preferred embodiment of my invention as illustrated in the drawings the tool is of the scissors type comprising the two jaws 1 and 2 with their shanks 3 and 4 pivoted at 5 on a rivet or bolt. The jaws are cut away at 6 to form a space there- 55 between, each jaw is provided with a

head as 7, which is formed by turning up the material of the heads at right angles thereto so that the two heads 7 are parallel with each other and contact when the jaws of the tool are closed. The heads project outwardly a suitable distance from their respective jaws, and the outer working edges at the inner ends of the jaws are provided with spaced recesses or grooves 8 of proper size and shape to fit over a wire. 60

Below the heads of the jaws and in position to co-act therewith an anvil 9 is pivoted, the bolt or rivet 5 of the pivoted shanks serving as the pivot of the anvil which is provided with a perforated shank 10 through which the pivot bolt 5 is passed. The anvil is preferably triangular in shape, and one of the apices is fitted with a pin 11 passed through a perforation and fixed therein, but of sufficient length to project 70 between the tool handles or shanks 3 and 4 to form an abutment for the purpose of restricting the pivotal movement of the anvil, and hold it always in operative position 75 with relation to the co-acting heads on the jaws. The operating face of the anvil is centrally recessed as at 12, the recess being curved, and the curved face of the recess is grooved as at 13. These grooves 13 are spaced in alinement with the grooves 8 of 80 the jaw-heads so that a groove in the curved face of the anvil may retain a staple while the pair of grooves 8 on the heads may "ride down" the ends of the wire staple 14 as will be described. 85

The wire staple 14 which may be formed either by means of the tool of the invention or of stock pattern is to be affixed to the slotted post 15 to attach the horizontal wire 16 by means of the tool. In use, the 90 staple is first passed through the slot 17 in the post with the fence wire 16 held in the staple as indicated in Fig. 5.

The function of the tool is to turn the ends of the staple to the position shown in 100 Figs. 4 and 5, and to this end, the tool is slipped over the edge of the flat metallic fence post 15, the closed heads at one side and the anvil at the other side of the post, and the heads 7 of the jaws are passed in 105 between the ends of the staple 14 as shown in dotted lines Fig. 4. The fence wire 16 passes through the cut away parts 6 of the jaws and the staple is held snugly up against the wire 16 by the anvil which is 110

pressed against the post so that the staple is partially embraced by one of the grooves 13 in the recess 12 of the anvil which fits around the staple head as in Fig. 4. The handles 3 and 4 are now grasped one in each hand and spread apart and the jaws are thus opened on their pivot 5. As the jaws are opened, the outer faces of the heads are brought into contact with the ends of the U-shaped staple and these ends are bent backwardly as the heads "ride" them down against the face of the fence post. The grooves 8 in the heads engage the ends of the staple and prevent the ends from being turned out of line with each other, and these grooves 8 guide the ends of the staple while the grooves 13 in the anvil hold the head or bent end of the staple against movement. In this manner the ends of the staple

are flattened against the post and the fence 20 wire 16 is rigidly held against the post.

What I claim is:—

1. A tool comprising crossed handles pivoted together and each formed with a jaw, integral heads on the jaws, and an anvil 25 having a wide operating face and pivoted on the pivot of the handles, and said heads adapted to co-act with and swing out over said face.

2. A tool comprising crossed handles pivoted together and each formed with a jaw, integral heads on the jaws turned at right angles thereto, and an anvil pivoted on the pivot of the handles formed with a curved face to co-act with said heads. 30 35

In testimony whereof I affix my signature.

WILLIAM KYLLONEN.
